GARMENT PRESS HAVING A STEAMING DEVICE

John Mallouf, Las Vegas, N. Mex.

Application October 18, 1944, Serial No. 559,209

2 Claims. (Cl. 38—15)

1

This invention relates to garment presses, and the primary object of the present invention is to provide, in a press of the above kind, a novel arrangement of steaming valve and operating mechanism therefor that is characterized by compactness, extreme simplicity, and pronounced efficiency of operation.

The exact nature of the present invention will become apparent from the following description when considered in connection with the accompanying drawings, and the invention consists in the novel form, combination and arrangement of parts hereinafter more fully described, shown in the drawings and claimed.

In the drawings, wherein like reference characters indicate corresponding parts throughout the several views:

Figure 1 is a fragmentary side elevational view of a garment press embodying a steaming valve arrangement and operating mechanism for the steaming valve, in accordance with the present invention.

Figure 2 is a top plan view thereof.

Figure 3 is an enlarged fragmentary view of the upper pressing member and parts associated therewith, the view being partly in side elevation and partly in section.

Figure 4 is an enlarged section taken on line 4—4 of Figure 2.

Figure 5 is an enlarged fragmentary sectional view of the steaming valve.

Referring in detail to the drawings, the press may be of any suitable form or construction that embodies two relatively movable pressing members between which the garment or material is pressed. As illustrated, the press comprises a suitable frame 5 carrying the lower pressing member 6 which may be heated by steam and padded as usual. The frame is provided with an upright 7 to which is pivotally connected the arm or lever 8 carrying the upper pressing member 9 and a counterweight 10. By swinging movement of said lever on its support, the upper pressing member can be pulled toward and from the lower pressing member and into and out of cooperative pressing relation therewith. Foot treadle-operated mechanism is usually provided for operating said lever for the application of more powerful pressure after the operator manually depresses the upper member or head 9 by the use of a handle 11. The upper pressing member 9 may be heated by steam supplied to its inner chamber through a pipe 12. The member or head 9 is also constructed to provide a suitable steaming device supplied with steam through a branch 13 of the

2

pipe 12. In this branch 13 is a steaming valve 14 capable of being opened to permit flow of steam to the steaming device by depression of its valve rod 15.

5 The operating mechanism for the steaming valve includes the handle 11 by means of which the operator initially manually depresses the member or head 9, prior to application of his foot to the treadle for production of more powerful pressure. Handle 11 is carried by supports 16 attached to or forming part of the lever 8, said handle being rotatable on its own axis relative to the supports 16. For the latter purpose, a pivot bolt 17 extends through the projecting forward ends of the supports 16, and the handle 11 is rotatably fitted on the bolt 17 between said supports 16, as clearly shown in Figure 4.

Rigid with and rising from the member or head 9 is a bracket 18 located rearwardly of steaming valve 14 and having the rear end of a lever 19 pivoted thereto for vertical swinging movement. Lever 19 is of angular form so as to extend forwardly across and in contact with the upper end of the valve rod 15, and then forwardly and downwardly to a point at the front of the member or head 9 intermediate the ends of the latter. Ordinarily, a lever somewhat similar to lever 19 is provided which has a finger piece at the forward end thereof adapted to be depressed for opening the steaming valve. This requires the use of the hand that is free and not used to grasp the handle 11, and necessitates reaching inwardly or rearwardly past the handle 11. The latter is not convenient, and it is objectionable because the operator should have a free hand for manipulating the garment and the like while the other hand is used to grasp the handle 11 and lower the member or head 9. To overcome this objection, I provide a pair of rearwardly converging arms 20 having clamps 21 on their forward ends that fit about and are securely fastened on the ends of the handle 11 at the inner sides of the supports 16. The arms 11 terminate at their rear ends in spaced parallel end portions 22 disposed against opposite sides of the forward end of lever 19, and a pivot bolt 23 loosely extends through the forward end of lever 19 and also through the rear ends of arms 20 so as to operatively connect the arms 20 to said lever 19.

40 From the above description, it will be seen that when the operator grasps the handle 11 with one hand, he may lower the member or head 9 toward the member 6. In so doing, the handle 11 is rotated in a counter-clockwise direction with respect to Figure 3, thereby swinging the arms 20 down-

45

50

55

wardly and causing similar movement of lever 19 so as to depress valve rod 15 and open the steaming valve 14. This causes steam to be supplied to the steaming device as the member or head 9 is being lowered, leaving one hand of the operator free to adjust the garment on the member 6, and for other purposes. Immediately prior to engagement of member 9 with member 6, the foot-operated mechanism may be utilized to force the member 9 with the desired pressure against the member 6, handle 11 being released so as to allow the valve 14 to close under the action of its spring 24. When this takes place, the valve rod 15 elevates the lever 19 and arms 20 so that the parts are returned to normal position for the next operation. The present invention essentially consists in the arrangement of the steaming valve and the operating mechanism therefor, which are such as to provide extreme simplicity of construction, compact arrangement of parts, and efficient operation. It is simply necessary that the handle 11 be released immediately before the head 9 engages the member 6 and to utilize the foot-operated mechanism immediately prior to release of the handle 11 to bring about the final lowering movement of head 9 and the desired pressure of the latter against the member 6. This slight amount of care will avoid supply of steam to the steaming device when the press is closed, without the use of special means for preventing this occurrence.

What I claim is:

1. In a garment press, a stationary lower pressing member, a vertically movable upper pressing member having a steaming device, a steaming valve for controlling flow of steam to the steaming device and arranged above the upper pressing member, said valve including an upwardly seating valve member having an upwardly projecting rod and a seating spring to allow closing of the said valve under its action, a bracket carried by the upper pressing member rearwardly of said steaming valve, a lever pivoted at one end to said bracket for vertical swinging movement, said lever extending forwardly across and in contact with the upper end of said valve rod and then forwardly and downwardly to a point at the front of the upper pressing member, spaced supports projecting forwardly from said upper pressing member at opposite sides of said lever, a handle disposed between and supported by the forward

15 20 25 30 35 40 45 50

ends of said supports, said handle extending transversely of the lever and rotatably mounted on its own axis, and at least one arm fixed to said handle and projecting rearwardly to a point beside the forward end of said lever, the rear end of said at least one arm being loosely pivoted to the forward end of said lever so that use of the handle in lowering the upper pressing member will effect depression of the arm and actuation of the lever to open the steaming valve.

2. In a garment press, the combination of a stationary lower pressing member, a vertically movable upper pressing member having a steaming device, a vertically swinging lever including spaced supports carrying and extending across said upper pressing member, a normally closed valve for controlling flow of steam to said steaming device, said valve being disposed above and having its outlet rigidly connected to the upper pressing member between said supports and including a member depressible to open the same, a bracket rigid with and rising from the upper pressing member behind said valve, a pivot bolt connecting the forward ends of said supports and having a handle rotatably mounted thereon, a pair of rearwardly converging arms clamped at their forward ends on the ends of said handle, a second lever pivoted at one end to said bracket and loosely pivoted at its other end to and between the rear ends of said arms, said second lever resting on said depressible member in position to depress the same when the handle is gripped and turned while swinging the upper pressing member downwardly.

JOHN MALLOUF.
